UNITED STATES PATENT OFFICE

JAMES T. COWLEY, OF SYRACUSE, NEW YORK, ASSIGNOR TO THE LAMSON COMPANY,
OF SYRACUSE, NEW YORK, A CORPORATION OF MASSACHUSETTS

DESK STATION FOR PNEUMATIC-DISPATCH SYSTEMS

Application filed October 10, 1927, Serial No. 225,080. Renewed March 25, 1929.

This invention pertains to terminal apparatus for carrier dispatch systems and more particularly to terminal apparatus of that type in which the necessary mechanical 5 appurtenances are partly or wholly concealed within an enclosing structure having the general external appearance and utilities of usual office furniture such, for example, as a desk, filing cabinet or the like. In such 10 installations the receipt and dispatch of carriers may be incidental or wholly supplemental to the principal duties of the operator seated at or standing within working range of the desk or cabinet and thus the arrangement 15 of the dispatch and delivery terminals should be such that they are readily accessible to the operator without interference with his other duties. In order to avoid undue noise when the carrier arrives, it is desirable to 20 house the delivery terminal at least within the desk, cabinet or the like, but this leaves the operator without notice of the arrival of the carrier, and the present invention 25 provides suitable signal means, preferably visible rather than audible, so that the operator may not neglect a carrier requiring his attention.

As herein disclosed by way of example the invention is embodied in a flat-top desk of 30 a usual type having a pedestal at each side of a central knee space, one of the pedestals having the usual drawers while the other contains a carrier-receiving compartment readily accessible from the front of the desk 35 through a normally closed opening. A signal device, for example a lamp, is energized upon the entrance of a carrier into the compartment and is automatically restored to inoperative condition by removal of the carrier 40 from the compartment. A dispatch terminal is also arranged within convenient reach of an operator stationed at the desk, such terminal being normally closed by a retractable gate. While, as here shown, the apparatus is 45 associated with a pneumatic conveyor system, it is broadly applicable to other systems such, for example as gravity systems, and I herein employ the terms "dispatch and delivery terminals" as inclusive of the terminals 50 of any type of system.

A typical embodiment of the invention will be described with reference to the accompanying illustrations, in which

Fig. 1 is a front elevation of the apparatus;

Fig. 2 is a cross section of the apparatus 55 along line 2-2 of Fig. 1;

Fig. 3 is a cross section of the apparatus along line 3-3 of Fig. 1;

Fig. 4 is a view similar to Fig. 3, showing the signal device installed therein;

Fig. 5 is a front sectional view (with parts broken away) of the signal device shown in Fig. 4;

Fig. 6 is a diagrammatic representation of the electric connections shown in Figs. 4 and 5; and

Fig. 7 is a side view of a modified form of the sending part of the apparatus, showing the pedals in raised and lowered positions.

Referring to the drawings, the illustrative embodiment of the invention includes generally a desk having a top 1, drawers 2, and if desired, a filing space 3, with a knee space 4 at the center to permit the operator to sit at the desk in the usual way. At the rear part of the desk, and standing above the desk top proper, are delivery and dispatch terminals 5 and 6, respectively, of a pneumatic dispatch system of known type. Preferably the delivery and dispatch tubes extend through the rear portion of the desk proper, and the terminals are housed within a suitable cabinet or housing 1^a setting upon or forming a part of the desk.

The delivery tube 7 terminates in a valve 8 having gravity balanced closing members 9. The arriving carriers pass freely through this valve 8 and are received in an airtight chamber 11 within the desk proper, such chamber preferably being at one side of the knee space. 90 This chamber has an extension 11^a within the cabinet or housing 1^a, and within this extension and the chamber proper there is arranged a guide member or chute 12 adapted to direct arriving carriers toward a door 13, 95 normally closing an access opening leading into the chamber 11. A return or suction air tube 14 leads from the delivery terminal 5 to the opposite side of the desk where it communicates with a vertically disposed end por-

tion 15 of a dispatch tube. The dispatch terminal comprises a receiver or short bell-mouth tube 10 which leads to the upper end of the dispatch tube. Interposed between the receiver 10 and the upper end of the dispatch tube is a gate member 17 which normally closes the end of the dispatch tube. This gate member is preferably mounted upon a lever arm 18 which is connected by a link 19 to a bell crank lever 21. The lever 21 is conveniently located under the desk in the knee space 4 and directly joined to a pedal 22, and also, through a link 23, to a forward pedal 24.

15 The desk may be provided with electrical conductors 26 forming portions of a circuit including a switch 27 which is adapted to be closed by the passage of a carrier through the valve 8. The closure of this switch energizes 20 a relay including solenoid 28 (see Fig. 6) and thereby moves a bar 28 which closes a holding circuit including conductors 30 and a switch 32 and the coils of the solenoid 28 and a second circuit 33 which includes a signal lamp 3. 25 The circuit including the conductors 30 is normally closed at the switch 32 so long as the door is closed.

As thus constructed and arranged, the desk may be used continuously with respect to the 30 proper treatment of the contents of the carriers, such as orders, etc., or collateral matters, the top, drawers and cupboard being freely available without interruption. When a carrier is discharged through the valve 8 35 and falls into chamber 11 it (or the valve 8) will strike and temporarily close the switch 27 and then roll down chute 12 against the door 13. The closing of switch 27 completes the primary circuit 26 through solenoid 28. 40 The relay solenoid is thereby activated, its electromagnetic force raising the member 29. The door 13 being normally closed, and likewise door switch 32, the bar 29 closes the circuit 30 which includes the solenoid 28 and also 45 closes the circuit 33 through the signal lamp 34, thus lighting the bulb and indicating that a carrier has entered the chamber.

The operator, who upon observing the signal is notified of the arrival of a carrier, opens 50 the door 13 and removes the carrier (36) Fig. 4. Upon opening the door the projection 35 of door switch 32 is retracted thus breaking the electric circuit 30. This renders the solenoid 28 inoperative, thus breaking the connection formed by the bar 29 in circuit 30 and also in the light circuit 33 through the signal lamp 34.

The door is then closed, whereupon switch 55 32 is automatically closed, and valve 8 is closed by the inrush of air. The apparatus is again in position to indicate the arrival of another carrier.

The contents of the carrier may now be 60 disposed of as required and the carrier re-

filled or returned to the system empty as the case may be.

When the carrier is to be returned to the system, it is closed and placed in the receiver 10.

If the operator is sitting at the desk, he now 70 presses down the rear pedal 22, thereby retracting the gate 17, and, permitting the carrier to fall through opening 16 into the dispatch tube 15, going past the end of return tube 14 and thence into the system in the usual manner. If he is standing in front of the desk, he may operate the forward pedal 24 to effect 75 the same result without sitting down. Upon releasing the pedal, the gate 17 is returned to its former position by spring 37, closing the opening at 16 and serving to hold a subsequent carrier in the receiver 10 until it is to be dispatched.

80 Thus the apparatus permits an operator 85 efficiently and effectively to attend to the incoming carriers and their contents, substantially without any possibility of oversight and yet without necessitating constant observation of the receiving compartment. Again, 90 the operator may remain standing or seated as the nature of his work may require and yet operate the receiving and sending elements 95 of the apparatus. Furthermore, the operator may leave the station altogether and be engaged elsewhere but so long as he is within sight of the signal device (or within hearing etc., if a bell or other signal is employed) he may still satisfactorily supervise the apparatus and operate it with regularity. 100 Moreover, the apparatus is competent to receive a plurality of carriers without clogging, and all may be removed through the door 13 in the order of their arrival.

105 It will be understood, by those familiar with the art, that numerous adaptations and modifications of the apparatus may and probably will be resorted to in actual practice with substantially equivalent results to those herein contemplated. But such modifications and adaptations are to be considered as comprehended in the above disclosure and included by the terms of the following claims.

I claim:

110 1. Apparatus of the class described, comprising a piece of usual office furniture provided with a compartment, a door normally closing an entrance to the compartment, a pneumatic tube terminal arranged to deliver carriers into the compartment, a suction tube 115 connected to said terminal, means normally closing the delivery terminal, said means opening automatically to permit a carrier to enter the compartment, and signal means to indicate the delivery of a carrier into the 120 compartment.

125 2. Apparatus of the class described, comprising a desk provided with a compartment, a door normally closing an entrance to the compartment, a conveyor tube terminal ar- 130

- ranged to deliver carriers into the compartment, a dispatch terminal within convenient reach of an operator stationed at the desk, means normally closing the delivery terminal, said means opening automatically to admit 5 an arriving carrier to the compartment, and electric signal means actuated by the arrival of a carrier to indicate the presence of a carrier in the compartment. 70
- 10 3. Apparatus of the class described comprising a piece of usual office furniture provided with a compartment, a door normally closing an entrance to the compartment, carrier conveying means having a terminal arranged to deliver carriers into the compartment, means normally closing said delivery terminal but opening upon impact of a carrier and closing the terminal after the passage of the carrier, a normally closed electric switch arranged to be opened when the door is opened, an electric signal device, and means operated by the opening of said closure means to establish an electric circuit through the door switch and the signal. 75
- 15 4. Apparatus of the class described comprising a piece of usual office furniture provided with a substantially air-tight compartment, a door normally closing an entrance to the compartment, a tube terminal arranged to deliver carriers into the compartment, a return transmission tube, closure means within the compartment, said closure means being normally closed but opening upon impact of a carrier and closing the terminal after 80 the passage thereof, an electric circuit including a normally closed switch arranged to be opened by the opening of the door, electric signaling means, and means operated by the opening of said closure means to establish a flow of electric current through said signaling means and circuit, the opening of said door breaking the electric circuit and cutting off current through the signaling means. 85
- 20 5. Apparatus of the class described including a desk having a flat top and a housing extending above the top, a compartment including portions within the desk proper and the housing, respectively, a conveyor tube terminal arranged to deliver carriers into that portion of the compartment which is within the housing, a normally closed door giving access to that portion of the compartment which is within the desk proper, a chute for conducting carriers from the terminal to 90 a point adjacent to the door, and signal means to indicate the presence of a carrier within the compartment. 100
- 25 6. Apparatus of the class described, comprising a desk having a flat top, a delivery terminal of a pneumatic dispatch system disposed above the rear portion of the top of the desk, a normally closed chamber within the desk arranged to receive carriers from the delivery terminal and adapted to retain a plurality of carriers, signal means to indicate 105 the arrival of a carrier from the delivery terminal, means permitting the removal of carriers from the chamber, and means associated with the removal means to return the signal means to inoperative condition. 110
- 30 7. Apparatus of the class described, comprising a desk having a flat top, a delivery terminal of a pneumatic dispatch system for carriers disposed above the rear portion of the desk top, a housing enclosing the terminal, the interior of the housing communicating with a chamber within the desk proper, an air return tube leading from the terminal to a dispatch tube, a normally closed receiver associated with the dispatch tube, said receiver being arranged at the rear part of the desk top, means permitting removal of carriers from the chamber, and foot pedal means for opening the receiver into the return tube for admitting carriers thereto. 115
- 35 8. Apparatus of the class described, comprising a desk having a flat top, a pneumatic delivery terminal disposed above the rear portion of the desk top, means normally closing the delivery terminal but opening under the impact of a carrier, the desk having a chamber for the reception of carriers delivered by the terminal, said chamber having a movable closure giving access to the chamber for removal of carriers therefrom, signal means for indicating the arrival of a carrier, a return air tube leading from the delivery terminal to a dispatch tube, a receiver associated with the dispatch tube, a gate interposed between the receiver and the dispatch tube, and foot 120 pedal means for moving the gate to admit carriers from the receiver into the dispatch tube. 125
- 40 9. Apparatus of the class described comprising a desk having a flat top, a pneumatic dispatch delivery terminal disposed above the desk top, means normally closing the delivery terminal but opening under the impact of a carrier, the desk having a normally closed chamber for the reception of carriers delivered by the terminal, a dispatch tube having its end portion within the desk structure, an air return tube connecting the delivery terminal to the dispatch tube, a receiver associated with the dispatch tube, a gate normally 130 interposed between the receiver and the dispatch tube, and means actuatable by the foot of the operator for opening the gate to admit carriers from the receiver to the dispatch tube. 135
- 45 10. Apparatus of the class described comprising a desk having a flat top, a pneumatic dispatch delivery terminal disposed above the rear portion of the desk top, the desk having a normally closed chamber for the reception of carriers from the terminal, a movable closure giving access to said chamber to permit removal of carriers therefrom, a dispatch tube, a receiver associated with the dispatch tube, a gate normally closing the receiving end of the dispatch tube, foot pedal means 140

for retracting the gate to admit carriers from the receiver to the dispatch tube, said gate normally being closed, and spring means for automatically returning the gate to closed position when the foot pedal is released.

11. Apparatus of the class described comprising a desk having a flat top, a pneumatic dispatch delivery terminal disposed above the rear portion of the desk top, the desk having a normally closed chamber for the reception of carriers delivered by the terminal, a movable closure giving access to the chamber to permit removal of carriers therefrom, a dispatch tube, a receiver for delivering carriers into the end of the dispatch tube, a gate normally closing the end of the dispatch tube, and foot pedal means including a front and a rear pedal independently actuatable for retracting the gate to permit carriers to pass from the receiver into the dispatch tube.

20. Signed by me at Syracuse, N. Y., this sixth day of October, 1927.

JAMES T. COWLEY.
